UNITED STATES PATENT OFFICE.

JOHN BOMA, OF ROCHESTER, NEW YORK, ASSIGNOR TO THE NATIONAL VOTING MACHINE COMPANY, OF SAME PLACE.

BOOTH FOR VOTING-MACHINES.

SPECIFICATION forming part of Letters Patent No. 590,942, dated September 28, 1897.

Application filed June 28, 1897. Serial No. 642,698. (No model.)

To all whom it may concern:

Be it known that I, JOHN BOMA, of Rochester, in the county of Monroe and State of New York, have invented a new and useful Improvement in Booths for Voting-Machines, which improvement is fully set forth in the following specification and shown in the accompanying drawings.

The object of my invention is to produce an improved inclosure or booth for voting-machines, the same being hereinafter fully described, and more particularly pointed out in the claims.

Referring to the drawings, Figure 1 is a front elevation of my improved booth. Fig. 2 is a side elevation seen as indicated by arrows 2 in Figs. 1 and 4, showing the side door which when opened reveals the result of the voting. Fig. 3 is a view of the partition seen as indicated by arrows 3 in Figs. 1 and 4, the walls of the booth being vertically sectioned, as on the dotted line at the point of the arrow in Fig. 1. Fig. 4 is a plan of the booth seen as indicated by arrow 4 in Fig. 1. Fig. 5 is an interior view of parts of the device seen as in Fig. 3, parts being broken away and the two opposite walls of the booth vertically sectioned. Fig. 6 is a plan of parts seen as indicated by arrow 6 in Fig. 5. Fig. 7 is a plan of some of the working parts, the walls being horizontally sectioned as on the dotted line 7 in Fig. 1, parts being shown in two positions by full and dotted lines. Fig. 8 is a horizontal section of a portion of the door, taken on the dotted line 8 in Fig. 9, with associated parts. Fig. 9 is an interior view, parts being vertically sectioned as on the dotted line 9 in Fig. 6 and viewed as indicated by arrow pointed thereon and arrow 9' in Fig. 4. Fig. 10 is a plan of parts of the device, the main door being horizontally sectioned as on the dotted line 10 in Fig. 9 and other parts horizontally sectioned as on the dotted lines 10' in Figs. 1 and 9. Fig. 11 is a plan, parts of the device being horizontally sectioned as on the dotted line 11 in Fig. 9, parts being shown in two positions by full and dotted lines. Fig. 12 is an outside elevation of the upper part of the booth seen as indicated by arrow 2 in Fig. 1, a part of the side door being broken away. Figs. 1 to 4,

inclusive, are drawn to a scale one-twentieth full size, Figs. 5, 6, 7, 9, and 12 are drawn to a scale one-seventh full size, and Figs. 8, 10, and 11 are drawn to a scale one-half full size. 55

Referring to the drawings, the booth shown is rectangular in plan, inclosing or comprising two apartments A' B', separated by a partition C', Figs. 4 and 6, the former apartment being occupied by the voter while voting and the latter apartment holding the voting-machine E'. The partition C' is not continuous, but is preferably formed of two parts, as shown in Fig. 6, in which the one to the right is thinner than and slightly out of line with the other or main portion that is shown to the left. The outer walls and partition of the booth are preferably made of light wood, though sheet metal may be used for the purpose. 70

The booth is without floor and provided with a main door D', Figs. 1, 3, 7, 9, 10, and 11, serving to close a passage through the front wall H' into the apartment A'. This door also when swung inward to place serves to close an opening through the partition or wall C' of the apartment B', forming temporarily a part of said partition or wall and covering an essential part of the voting-machine. The walls H' and C' are at right angles with each other, and the openings through them are alike as to size, so that the door fills and closes either one equally well when swung to either place, each opening forming a seat for the door. The booth is also formed with a smaller side door F, Figs. 2 and 12, serving to close an opening through the outer side wall N of the apartment B'. 80

The voting-machine E' in the apartment B' may be of any kind—as, for instance, one in which the swinging of the main door D' performs an essential part of the operation of voting—the machine shown being the same fully illustrated and described in my pending application for patent, Serial No. 638,950, filed June 1, 1897. The iron frame B of the machine is inclosed in a thicker wooden frame O, which is secured by simple fasteners b', Figs. 5 and 6, to the wall N. 90

Normally when the booth is being used at an election the door D' occupies its place in the wall or partition C' to cover and inclose

the voting-machine, which leaves a free entrance for a voter into the apartment A'. When a voter enters said apartment for the purpose of voting, he immediately swings the door from its place in said partition C' to its place in the front wall H'. This swinging of the door in the first instance uncovers the voting mechanism, giving the voter free access to the same, and in the second instance closes 10 the booth to outsiders, so that he may, in secret, operate the voting-machine to record his vote. The door thus has two functions. It serves in one case to close the apartment B' and cover the voting-machine and in the other case to close the booth as a whole.

The door is provided with an ordinary lock with knobs *aa* and latch-bolt *b*, Figs. 1, 9, and 11. The door is also secured or locked in its inner closed position in the wall C' by a long 20 horizontal latch-bolt *c*, Figs. 7, 8, and 9, inaccessible to the voter in the apartment A'. This latch-bolt is operated by means of an external knob *d*, Figs. 1, 3, 10, and 11, operated by the attendant of the booth on the outside 25 of the latter. This knob carries a bolt *e'*, (clearly shown in Fig. 10,) extending horizontally through the wall H of the booth into the apartment B'. The latch-bolt *c* is just above the bolt *e'*, and it is formed with an 30 outwardly-extended part *f'*, extending at its outer end over the bolt *e'* when the door is swung to the partition C', as clearly shown in Fig. 11. The bolt *e'* is provided with a vertical pin *g'*, (see also Fig. 9,) back of which 35 the part *f'* passes when the door occupies its said position.

The outer end of the part *f'* is slanted at its rear side so as to readily glide in back of the pin *g'* to the position shown in Fig. 11, 40 the bolt *e'* slightly yielding back to allow the part *f'* to pass the pin. Now if the knob *d* be pulled outward, as indicated by dotted lines, the latch-bolt *c* will be drawn out of its socket *h* in the wall C' and so release the door. 45 The bolt *e'* is held normally inwardly by an ordinary spring *c'*, Fig. 10, and when a voter enters the apartment A' the attendant at the outside pulls the knob *d* to release the door to enable the voter to swing it, as above described. 50 The part *f'* of the latch-bolt *c* being back of the pin *g'* does not impede the swinging of the door away from the wall C', as the beginning of the motion of the door is straight to the right (see Fig. 11) or away 55 from the pin, and a very slight springing or yielding of the parts serves to release them.

The latch-bolt *c* is provided with a rigid block *i*, held by a fastener *k*, Figs. 8 and 9, occupying a horizontal cavity in the door D'. 60 Within this cavity is a spring *l*, which, bearing against the block, tends to hold the latch-bolt normally in its extended position, so as to enter the socket *h*, the pulling of the knob *d* outward, as above described, to release the 65 door being done against the action of this spring.

In this invention the swinging of the main

door is designed to play an essential part in operating the mechanism of the voting-machine. By means of suitable intermediate 70 mechanism it returns all of the parts of the voting-machine to their normal positions after they have been manipulated or moved by a voter, and "sets" the machine for the use of the next voter. A lever E, Figs. 4, 5, and 75 6, is employed above the voting-machine to operate the latter, connected by a rod *f* and arm *g* with a shaft D. This shaft is adapted to move bars C in vertical directions which 80 act to move the operating parts of the voting-machine, as fully shown and described in my said pending application. The parts A B C D L and *e f g* here shown correspond with the parts referred to by the same letters in said pending application. 85

Upon the inside of the door D' is secured a rest *m*, Figs. 6 and 9, holding a horizontal arm *n*, reaching through the partition C' into the apartment B'. The arm *n* operates a bell-crank lever *o*, held to turn on a rest *p*, 90 rigid with the wall H of the booth. The outer end of the bell-crank is connected with the lever E by means of a rod *r*, so that when the door is swung upon its hinges it operates the lever E to move the working parts of the 95 voting mechanism—that is to say, when the door is swung to its place in the partition C' it pulls the lever E downward and so raises the bars C to return the parts of the voting mechanism to their normal positions, and when the door is swung to the front wall H' of the booth it serves to depress the bars C and so set the voting mechanism for the use of a voter.

Now as swinging the door D' puts the voting-machine in order for the use of a voter, such voter, after having entered the apartment A' and voted, might with fraudulent intent open the door under some pretense, as asking the outside attendant a question, and then close it again, and thus be afforded an opportunity to repeat his vote. To prevent this, I employ a notched bar *s*, Figs. 7, 9, 10, and 11, connected with the door and so controlled as to prevent the door being swung in 110 a manner to make it possible for a second vote to be recorded by the voter within. This notched bar is held by a holder or rest *t*, secured to the door, with its free end passing through a slotted guide or rest *u*, secured to 115 the front wall H of the booth. This guide is pierced by the bolt *e'*, the outer slanting end of the bolt being near the opening *v* in the guide through which the bar *s* passes, the latter being formed with a tooth or shoulder 120 *w* in position to be engaged by the bolt, as shown. This tooth or shoulder is located upon the bar so as to be engaged by the bolt when the door is turned through about forty-five degrees of arc from either of the walls 125 H' or C'. Thus when the door is swung back from the partition C' through an arc of forty-five degrees, more or less, the bolt will catch the tooth *w* and prevent the further swing-

ing of the door in that direction until the bar *s* is released by the knob *d* being pulled outward, as above described. This prevents the door being swung through a distance necessary for resetting the machine for another vote and prevents the possibility of a second vote being recorded until the door has been swung practically from one closed position to the other.

- 10 Furthermore, the construction and arrangement of the parts are such that the door acts upon the mechanism connecting it with the voting-machine only while swinging through a part of the way between its two extreme or 15 closed positions, it idling or doing nothing to said mechanism while passing through the other parts of its swings. On account of this the door may be swung through a considerable distance back from either wall *H'* or *C'* 20 without in any way affecting the voting-machine. This allows the attendant on the outside to partially open the door when closed against the wall *H'* and pass into the apartment *A'* to examine the voting-machine, 25 should anything go wrong, without working the machine. It also aids to prevent a voter from voting twice in quick succession, for after having voted once if he should attempt to swing the door for the purpose of putting 30 the machine in position for voting again it would be caught by the bar *s*, as above described, and prevented from swinging through a distance necessary for setting the machine for another vote. This I accomplish by elongating the opening *x*, Fig. 9, in the arm *n*, 35 which receives the pin *y* of the bell-crank *o*. When the door is in the position shown in the wall *H'*, the pin is at the left in the opening or slot *x*. Now if the door be swung 40 away from the wall the arm *n* will be moved toward the left, but the bell-crank will not be moved until the right-hand part of the slot or opening reaches the pin. The distance through which the door may thus swing 45 without acting upon the bell-crank depends upon the length of the slot or opening, which may be determined to suit circumstances, provided always that sufficient motion be given the bell-crank for the purpose intended. 50 The door needs to be swung practically home to its place in the wall *C'* to return the parts of the voting-machine to their normal places, and to its place in the wall *H'* to set the machine for another vote. When the 55 door is with the wall *H'*, it may be swung away therefrom some distance without acting on the machine, its effective work being accomplished only when moving through the latter part of its swing toward the wall *C'*, and when 60 the door is with the wall *C'* it may be swung some distance away therefrom without acting on the machine, its effective work being accomplished only while moving through the latter part of its swing toward the wall *H'*. 65 Swinging the door against the partition or wall *C'* returns the parts of the machine to

their normal places, as has been stated, but no part of the machine could then be voted, even if accessible to the voter, for although the parts of the machine are in their normal 70 positions they are not yet at liberty to be moved. The door needs to be swung back to the wall *H'* to leave the parts of the machine free to move. When a voter enters the apartment *A'* and closes the door after him against 75 the wall *H'*, the machine is ready for him to vote, and after voting he swings the door from said wall to its place against the wall *C'*, which makes the booth ready for the next voter.

In using the voting-machine shown and described in my pending application above referred to the voter stands on one side of the same to manipulate the parts to record his vote, while upon the other side of the machine the result of the voting is shown by figures. 80 It is the former side of the machine that is adjacent to and covered by the door *D'* in my present invention, and the latter side of the machine that is opposite and covered by the side door *F*. (Shown in Figs. 1 and 12.) 85 Now by opening the door *F*, which is normally shut and securely locked at the close of an election the result of the voting may be at once read off from the machine.

One aim in designing this booth is to so construct it that it may be taken apart and packed in small compass for the purpose of storing during periods between elections. To accomplish this, I make the sides or outer walls *I* and *K*, Fig. 4, and a part *H'* of the 90 front wall removable from the other walls of the booth. The walls *H*, *C'*, *P*, and *N*, inclosing the apartment *B'*, are rigid together, the door *D'* being hinged to the wall *H* at the junction of said wall and the wall *C'*, and 95 when the detachable walls are removed said door is swung to its place in the wall *C'* and securely locked.

In packing the booth for storage the removable walls are detached and all parts laid together. The part or piece *S* is used for architectural effect and for the purpose of being lettered with the name of the inventor, manufacturer, or otherwise, and is detachable from the parts *H* *H'* of the front wall. The line of 100 parting of the walls *K* and *P* is at *d'*, Figs. 4 and 6, and the line of parting between the walls *H* and *H'* is at *h'*, Figs. 1, 4, and 6. The detachable walls are connected with each other and with the part inclosing the machine 105 by simple fasteners or hooks *z*, Figs. 5, 6, and 9. When the booth is set up for use, these walls or sides are hooked to place to form the complete booth comprising the two apartments *A'* *B'*, hereinbefore described. 110

What I claim as my invention is—

1. A booth for a voting-machine, having an apartment to be occupied by the voter, and another apartment for containing the voting-machine, with a partition between the apartments formed with a doorway through it, and a door to close said doorway, a fastener to

hold the door in its closed position, and means to unfasten the door from outside of the walls of the booth, substantially as specified.

2. A booth for a voting-machine, having an interior partition with a doorway through said partition, and a doorway through an outer wall of the booth, and a door held by the booth adapted to close either of said doorways, substantially as and for the purpose set forth.

10 3. A booth for a voting-machine, having an apartment to be occupied by the voter, and another apartment for containing the voting-machine, with a partition between the apartments formed with a doorway through it, and 15 a doorway through the adjacent outer wall of the booth, and a door held by the booth adapted to close either of said doorways, and a window opening into the apartment occupied by the voter, substantially as described.

20 4. A booth for voting-machines, having an apartment to be occupied by the voter, and another apartment for containing the voting-machine, with a partition between the apartments formed with a doorway through it, and 25 a doorway leading from without into the apartment occupied by the voter, and a door adapted to close either of said doorways, and a door leading from without into the apartment containing the voting-machine, substantially as 30 shown and described.

5. A booth for voting-machines, having an interior partition, and a doorway through said partition and through the outer wall of the booth, and a door adapted to close either of 35 said doorways, and means for holding the door between said doorways, substantially as shown and described.

6. A booth for voting-machines, having an interior partition, and a doorway through said 40 partition and through the outer wall of the booth, and a door adapted to close either of said doorways, and means for holding the door between said doorways and for releasing the door from outside of the walls of the 45 booth, substantially as described.

7. A booth for a voting-machine, having a door, and a lever for operating the voting-machine, and connectors for said door and lever whereby when the door is swung the 50 lever will be turned upon its fulcrum, substantially as and for the purpose set forth.

8. A booth for a voting-machine, having an interior partition, and a doorway or opening through said partition and through the adjacent outer wall of the booth, and a door adapted to close either of said openings, and a lever for operating the voting-machine, and connectors for said door and lever whereby when the door is moved to close one of said 55 openings the lever will be turned in one direction, and when moved to close the other of said openings the lever will be moved in the opposite direction, substantially as specified.

65 9. A booth for a voting-machine, having an interior partition, and an opening through

said partition and through the outer wall of the booth, and a door adapted to close either of said openings, and a lever for operating the voting-machine, and connectors for said door and lever whereby when the door is moved to close one of said openings the lever will be turned in one direction, and when moved to close the other of said openings the lever will be moved in the opposite direction, 70 and means for causing the door to act upon the lever only while swinging through a part of the distance between said openings, substantially as and for the purpose specified.

10 10. A booth for a voting-machine, having an interior partition, and a door adapted to swing against said partition and also against an outer wall of the booth, and mechanism connected with the door for operating said voting-machine, and means for causing the 85 door to actuate said mechanism during the latter part only of its swinging motion in either direction, substantially as shown and described.

11. A booth for voting-machines, having an interior partition and a door adapted to swing against said partition and also against the outer wall of the booth, a sliding bolt upon the door for locking it against the partition, a bolt through the wall of the booth, the inner end of which is provided with a catch and an extended part upon the sliding bolt for engaging with the catch, substantially as set forth.

12. A booth for voting-machines, having an interior slotted partition and a door adapted to swing against said partition and also against the outer wall of the booth, a sliding bolt upon the door, one end of which is adapted to engage with the partition and the other end is provided with an extended part, adapted to extend through the slot of the partition, a spring-actuated bolt through the wall of the booth, the inner end of which is provided with a pin adapted to engage with the extended part of the sliding bolt, whereby the sliding bolt is unlocked from the partition when the other bolt is drawn out, substantially as set forth.

13. A booth for voting-machines, having an interior partition and a door adapted to swing against said partition and also against the outer wall of the booth, a slotted guide upon the wall of the booth adjacent to the hinge of the door, a bar pivotally secured to the door, the free end of which is notched and adapted to slide through the guide, a bolt through the wall of the booth, the inner end of which is adapted to engage with the notched portion of the bar and prevent the swinging of the door from the partition to the outer wall of the booth, and means connected with the door for operating the voting mechanism only after the bar has been released from the bolt, substantially as set forth.

14. A booth for voting-machines, having an interior partition and a door adapted to swing

against the partition and also against the outer wall of the partition, a sliding bolt upon the door, one end of which is adapted to engage with the partition and the opposite end is provided with an extended part, a notched bar pivotally secured to the door, a bolt through the wall of the booth, the inner end of which is adapted to engage with the bar and with the extended part, and means for

connecting the end door with the voting mechanism, substantially as set forth.

In witness whereof I have hereunto set my hand, this 22d day of June, 1897, in the presence of two subscribing witnesses.

JOHN BOMA.
